Inventor:
Fitz Girard
by A. M. Neumann
Attorney.

UNITED STATES PATENT OFFICE.

FRITZ GIRARD, OF HANAU-ON-THE-MAIN, GERMANY.

QUARTZ LAMP.

Application filed August 24, 1921. Serial No. 494,981.

(GRANTED UNDER THE PROVISIONS OF THE ACT OF MARCH 3, 1921, 41 STAT. L., 1313.)

To all whom it may concern:

Be it known that I, FRITZ GIRARD, a citizen of Germany, residing at Hanau-on-the-Main, Germany, have invented certain new and useful Improvements in Quartz Lamps (for which I have filed applications for patents as follows: Germany, June 13, 1914, Patent 287055; England, June 14, 1915, Patent 8753/15; France, June 12, 1915, Patent 511314; Austria, June 12, 1915, Patent 73952; Hungary, June 11, 1915, Patent 69160), of which the following is a specification.

My invention refers to quartz lamps and more particularly to a safety device for use in connection with such lamps. It is an object of my invention to protect the persons using such lamps from getting injured in the case of a lamp breaking.

As is well known to those skilled in the art, there is a defect inherent in quartz lamps which resides in the fact that if a lamp should break when in use incandescent particles of quartz drop and the boiling hot mercury flows out. Such breakage is not of great importance in the case of quartz lamps that are employed for illuminating purposes as such lamps are provided with glass globes. It is different, however, with quartz lamps employed for medical purposes as they must invariably fulfil the condition of causing no injury to the patient in case of breakage.

An effective safety device must be composed of a material which is permeable to the ultra-violet rays which are required when quartz lamps are used for medical purposes and moreover it must be arranged in such a manner that injury to the person by the falling of incandescent pieces of quartz or the escape of the hot mercury is prevented. The object of the present invention is to fulfil these requirements.

In the drawings affixed to this specification and forming part thereof, a device embodying my invention is illustrated diagrammatically by way of example. In the drawings—

Fig. 1 is a longitudinal section, and

Fig. 2 a cross section of the burner of a quartz lamp with the safety device applied to it.

Referring to the drawings, *a*, *a* are two pressed metal caps enclosing the pole chambers of the lamp as closely as possible and cut away to a semi-circular form where the lighting tube is fitted. They serve to support the semi-cylindrical quartz protecting trough *b* which may either consist of completely clear material or which may be provided at the lower part *c* (Fig. 2) with a thin layer of milk-white quartz so that the most intense rays of light which are emitted vertically downwards are somewhat screened. A milk-white glass more or less permeable to the ultra-violet rays may be employed in place of quartz.

The protecting device may, if desired, be formed as a tube wholly surrounding the lamp.

I wish it to be understood that I do not desire to be limited to the exact details of construction shown and described, for obvious modifications will occur to a person skilled in art.

I claim:

1. In a quartz lamp in combination, two pole chambers, a lighting tube extending substantially longitudinally intermediate said chambers, a metal cap below each pole chamber and a protective trough permeable to ultra violet rays supported by said caps and partly surrounding said tube.

2. In a quartz lamp in combination, two pole chambers, a lighting tube extending substantially longitudinally intermediate said chambers, a metal cap below each pole chamber and a protective trough of quartz supported by said caps and partly surrounding said tube.

3. In a quartz lamp in combination, two pole chambers, a lighting tube extending substantially longitudinally intermediate said chambers, a metal cap below each pole chamber, a protective trough of clear quartz supported by said caps and partly surrounding said tube and a thin layer of translucent quartz on the bottom of said screen.

In testimony whereof I affix my signature.

FRITZ GIRARD.
